AUTOMATIC WRAPPING MACHINE

Alvin O. Shafer, Lansing, Mich., assignor to
 Rikerd Lumber Company, Lansing, Mich., a
 corporation of Michigan

Application November 3, 1934, Serial No. 752,601

12 Claims. (Cl. 93—2)

This invention relates to automatic wrapping machines and more particularly to machines of that character adapted to permanently apply preformed paper wrappers to wood blocks.

5 The many advantages and novel features of the present invention will fully appear in the following description when read in connection with the accompanying drawings. A brief outline of the construction and operation of the machine is 10 here given as a preface to the detailed description which will follow.

As indicated above, the principal object of the invention is the provision of a machine adapted to permanently apply preformed wrappers to 15 wood blocks. The machine embodying the invention includes an endless carrier for the wood blocks to be wrapped and a movable carrier for the preformed sections of wrapping material. The actual wrapping of the blocks is effected in 20 a portion of the machine identified as the forming box.

Suitable mechanism is provided for applying adhesive to a section of the preformed wrapping material and thereafter delivering that section to 25 a position adjacent an inlet opening to the forming box. Immediately after the section of wrapping material is placed in position adjacent the opening of the forming box, a block to be wrapped is positioned adjacent but in spaced relation to 30 the wrapping material.

When the block and wrapping material have been properly aligned with each other and the inlet opening of the forming box, a plunger forces the block against the wrapping material and into 35 the forming box between a series of rollers which press the wrapping material against four sides of the block, causing it to adhere firmly thereto. Thereafter a second plunger forces the block and wrapping material out of the box through an outlet opening between a second series of rollers which press the wrapping material against and 40 seals the same to the other two surfaces of the block.

The foregoing operations are automatically repeated at suitable intervals so that there is a 45 continuous flow of blocks and wrapping material into the forming box.

In the accompanying drawings:

Figure 1 is a top plan view of the machine embodying the present invention;

Figure 2 is a side view in elevation of the machine shown in Figure 1 with one side of the frame removed;

Figure 3 is a plan view of a section of preformed wrapping material employed;

Figure 4 illustrates the position of the block and wrapping material before the forming operations;

Figures 5 to 7 inclusive illustrate diagrammatically the mechanism for applying a preformed section of wrapping material to a block;

Figure 8 is a diagrammatic illustration in elevation of the driving mechanism forming a part of the machine illustrated in Figures 1 and 2;

Figure 9 is a top plan view of the driving mechanism illustrated in Figure 8;

Figure 10 is a sectional view of the machine taken on substantially the line 10—10 of Figure 1;

Figure 11 is a sectional view taken on substantially the line 11—11 of Figure 1;

Figure 12 is a sectional view taken on substantially the line 12—12 of Figure 1;

Figure 13 is a partial plan view of the machine illustrating the stripper, picker and conveyor mechanism;

Figure 14 is a view taken on substantially the line 14—14 of Figure 11;

Figure 15 is a view taken on substantially the line 15—15 of Figure 11;

Figure 16 is a view taken on substantially the line 16—16 of Figure 2;

Figure 17 is a view taken on substantially the line 17—17 of Figure 2;

Figure 17a is a partial view of the picker pitman and operating cam;

Figure 18 is a view taken on substantially the line 18—18 of Figure 10;

Figure 19 is a view taken on substantially the line 19—19 of Figure 18;

Figure 20 is a sectional view taken on substantially the line 20—20 of Figure 18;

Figure 21 is a side view in elevation of a portion of the picker mechanism;

Figure 22 is a bottom plan view of the picker mechanism illustrated in Figure 21; and

Figure 23 is a sectional view taken on substantially the line 23—23 of Figure 22.

As illustrated in Figures 1 and 2 the machine embodying the present invention is supported upon and positioned between two frame members 10. The frame merely serves as a support and protection for the operating mechanism.

The machine is adapted to permanently apply a section of wrapping material 20 of the shape illustrated in Figure 3 to a wood block 15 which is illustrated in Figures 4, 11 and 15. A section of wrapping material 20 coated with adhesive and a block 15 are delivered to a position adjacent the inlet opening of a forming box 17 and are thereafter forced through the forming box where-

5 by the wrapper is permanently secured to the block. The section of wrapping material is delivered to the forming box 17 before the block 15. The mechanism for applying adhesive to the wrapping material and for delivering the same to the forming box will now be described. The mechanism for delivering the blocks 15 to the forming box will be described later.

10 Referring to Figure 3 it will be observed that the wrapping material 20 is preformed in the shape of a cross. The longer portion of the cross is designed to cover four sides of the block and the two arms of the cross the other two sides of the block.

15 *The elevator*

20 A quantity of these preformed sections of wrapping material is placed on a vertically movable carrier or elevator 21 slidably mounted on vertical frame members 21a and 21b (see Figures 2, 10, 12 and 17). The elevator includes a platform 22 positioned at the upper extremity thereof. Four vertical guide members 24 are mounted upon a stationary cross member 25 of the frame. These guides are positioned with respect to the 25 platform 22 of the elevator 21 whereby to properly position the sections of wrapping material 20 upon the same. The guides 24 contact the sections of wrapping material at the intersection between the long and short portions thereof. 30 The guides 24 are adjustably secured to table 25 at their lower extremities whereby they may be properly aligned to hold the wrapping material in the desired position. A retention spring 24a is secured to each of the guides 24 adjacent the 35 upper extremity thereof. These springs include finger portions overlying the top section of wrapping material 20. As will be described herein-after, springs 24a prevent the removal from the elevator 21 of more than one section of wrapping material at a time.

40 *The picker*

45 The wrapping material 20 is removed from the elevator 21 one section at a time by a picker 26 (Figs. 10, 12, 17, 21 22 and 23). In order to properly position the wrapping material for contact by the picker the elevator is raised from time to time during the operation of the machine until the supply of wrapping material carried on the platform 22 is exhausted. When this 50 occurs the machine is automatically stopped. The mechanism for raising the elevator is dependent for its actuation upon the picker mechanism. A description of the same will be deferred until the picker mechanism has been described.

55 As previously described, the preformed sections of wrapping material 20 are in the shape of a cross. The picker 26, which is best shown in Figures 21 to 23 inclusive, likewise includes a contact surface in the shape of a cross which is adapted to completely cover the surface of one section of wrapping material. The picker 60 removes the wrapping material from the elevator one section at a time. Briefly, this is accomplished by applying adhesive to the picker and then pressing the picker against a section of the wrapping material, the adhesive on the picker 65 causing the wrapping material to adhere thereto. As the picker is moved away from the elevator, one section of wrapping material is removed from the elevator. Recesses 26c are provided in the picker 26 (see Figs. 22 and 23) for the reception 70 of finger portions of retention springs 24a when

the picker contacts the uppermost section of wrapping material on elevator 21. As the picker removes the uppermost section of wrapping material the fingers release that section but snap back to prevent the underlying section from being removed also.

10 After the section of wrapping material is picked up by the picker it is then necessary to strip the wrapping material from the picker. This is accomplished by mechanism referred to 15 as a stripper. As the wrapping material is stripped from the picker a conveyor engages the wrapping material and transfers it to the forming box 17, all as will be described more in detail presently.

15 The picker proper, as indicated in Figures 21 to 23 inclusive, is in the form of an aluminum head attached to a base 27 by screws 28. The base includes a projection 29 by means of which the picker is connected to a reciprocal plunger. It 20 is important that the picker head 26 be formed of some material to which adhesive may be readily applied and which will transfer the adhesive to and distribute the same uniformly over a section of the wrapping material 20. While it 25 is preferred to utilize an aluminum head for this purpose, other materials having these requisite characteristics may be employed if desired.

20 The picker head is provided with a plurality of longitudinal and transverse grooves or channels 26a and 26b which receive the strands of wire forming the stripper and permit the contact surface of the picker to project through the stripper and engage a section of the wrapping material. Two of the longitudinal recesses are enlarged to 35 permit the passage therethrough of a portion of the conveyor.

25 The projection 29 of picker 26 is secured to the lower extremity of a vertical plunger 30 (Figs. 2, 10). For the purpose of guiding the picker 40 the plunger 30 is mounted within and extends through a bearing 31 carried by the cross frame member 32. At its upper extremity the plunger 30 is pivotally connected to the free extremity of link 33. The opposite extremity of link 33 is 45 pivotally connected to the frame 10 as indicated at 34. The connection at 34 is such as to permit some longitudinal play between the link 33 and the stationary member to which it is pivotally connected.

50 The plunger 30 and the picker 26 connected thereto are reciprocated vertically by means of a pitman 35 pivotally connected to link 33 at its upper extremity and operatively associated with a conventional cam 36 at its lower extremity. 55 Cam 36 is secured to shaft 37 which is driven by means of a suitable belt 38 from the main drive shaft 39. A spring 33a secured to link 33 and cross frame member 32 tends to hold it in its lowered position.

60 *Adhesive applying mechanism*

65 At the upper limit of movement of the picker 26 adhesive is applied to the contact surface thereof by the mechanism now to be described. An adhesive container or glue pot 40 is positioned on a support 41 secured to the frame 10 as indicated in Figures 1, 10 and 19. A roller 42 is mounted to rotate in the pot 40 with at least a portion thereof in contact with the adhesive 70 contained within the pot. Roller 42 is mounted upon a shaft 43 which is journaled in bearings 44 at opposite sides of the pot 40. The ends of roller 42 are recessed to receive the bearings 44 which are supported by the supporting members 75

45 and held in position, to act as a seal whereby to prevent the escape of adhesive from the pot along the shaft 43, by means of screw threaded devices 46 mounted upon frame members 45 so as to press against the outer ends of bearings 44.

Shaft 43 extends beyond the adhesive container 40 at both sides thereof (see Fig. 18). At one side there is associated with the shaft a clutch arrangement 47 to facilitate the demounting of the adhesive container without dismantling the entire machine. The clutch includes a sprocket wheel 48 by means of which the shaft 43 is rotated. A drive chain 49 passes over idle wheel 48a and operatively connects wheel 48 with the drive wheel 50 carried on shaft 51. Shaft 51 is rotated through suitable belt and pulley connections with auxiliary drive shaft 52 (see Figs. 8 and 10).

A scraper 53 is provided to assure the even distribution of adhesive on the roller 42. The scraper is pivotally mounted on the frame 45 as shown in Figure 19. A plurality of adjusting screws 54 are positioned behind the scraper 53 whereby the scraper may be accurately adjusted to vary the quantity of adhesive carried by roller 42. This is an essential feature of the present invention because of the fact that ultimately adhesive is distributed over substantially the entire surface of the section of wrapping material. It is important that the entire surface of the wrapping material be covered and yet that there be no globules or lumps in the adhesive, as that would impair the appearance of the finished article and prevent a satisfactory seal of the wrapper to the block.

Adhesive is first transferred from roller 42 to a travelling roller 55 and from roller 55 to the contact surface of picker 26. Roller 55 (Figs. 10, 19) is mounted upon a support 56 which is in turn mounted upon the bearing rods 57. Rods 57 are supported from the cross frame member 32 by a yoke 58.

Roller 55 is moved transversely of the machine in and out of contact with roller 42 by means of a drive connection with cam 59 which is mounted upon shaft 181. This connection includes a link 60 pivotally connected to the roller support 56, a lever 61 pivotally connected at its upper extremity to link 60 and pivotally connected at its lower extremity to a subframe member 62. A pitman 63 has one end thereof connected to cam 59 in a conventional manner and its opposite end pivotally connected to lever 61. By means of the connections 60, 61 and 63 the roller support 56 is actuated to move back and forth along the bearing rods 57.

When the traveling adhesive roller 55 is moved to the left (Fig. 10) it contacts the stationary adhesive roller 42 in adhesive pot 40. At the same time a gear wheel 64 at one end of roller 55 contacts gear wheel 65 at the corresponding end of shaft 43 whereby roller 55 is positively rotated against roller 42. In this manner adhesive is transferred from roller 42 to roller 55 uniformly. It will be observed that gear 64 associated with roller 55 is smaller than gear 65 associated with the shaft carrying roller 42. Consequently roller 55 is rotated faster than roller 42. This difference in speed of the two rollers facilitates the transfer of adhesive to roller 55.

Considerable difficulty is frequently experienced in obtaining an even distribution of adhesive on roller 55. To overcome this difficulty cam 59 is designed to hold roller 55 against roller 42

while the latter makes one complete revolution and then to move roller 55 slightly away from roller 42 while the latter makes another complete revolution. In this manner any film or excess of adhesive which is built up along the line of contact between the two rollers during the first complete revolution is permitted to drop back into adhesive pot 40 during the second revolution. Immediately below the line of contact between rollers 42 and 55 is positioned a wire 55a (Fig. 19) which helps to strip from roller 55 any excess of adhesive which may have collected thereon. The direction of rotation of rollers 42 and 55 is indicated by the direction arrows in Figure 19.

Adhesive is transferred from roller 55 to picker 26 when the support 56 is moved along bearing rods 57 to the right of Figure 10. It has been found essential to rotate roller 55 during the period of contact between that roller and picker 26 in order to obtain an even distribution of adhesive over the contact surface of picker 26. For this purpose there is provided a series of stationary teeth 66 (Figs. 11 and 14) which are engaged by the teeth of gear wheel 64 associated with roller 55. As the roller 55 approaches the picker 26, gear wheel 64 meshes with the teeth 66 causing the roller 55 to be rotated against the contact surface of picker 26. Teeth 66 are mounted upon cross frame member 67.

After the roller 55 has passed over the contact surface of picker 26 and moved to the right thereof (Fig. 10) picker 26 is actuated to move downwardly into contact with the uppermost section of the wrapping material 20 positioned on elevator 21. The adhesive on the contact surface of picker 26 enables the picker to pick up one section of the wrapping material and lift it away from the elevator. The section of wrapping material is then stripped from the picker by the stripper mechanism now to be described.

The stripper

The stripper mechanism, as best shown in Figures 10, 12 and 13, consists of a frame 70 supported by the conveyor track 68 immediately over the elevator 21. The conveyor track, consisting of two spaced apart members, is in turn supported from the table 25 by means of a plurality of upright supports 69. A plurality of wires 71 and 72 are secured to frame 70. The wire 71 is arranged longitudinally of the wrapping material carried on elevator 21 and the two spaced apart wires 72 are arranged transversely of the wrapping material. Conventional tightening arrangements, as illustrated at 73, are employed for keeping the wires 71 and 72 tight.

At the upper limit of its movement the picker 26 is positioned above the stripper with the longitudinal recess 26a in alignment with wire 71 and with transverse recesses 26b in alignment with the wires 72. When the picker is actuated by the pitman 35 to move downwardly the recesses 26a and 26b receive the wires 71 and 72 respectively, and permit the contact surface of the picker to project below the wires and engage the top surface of the uppermost section of wrapping material on the elevator 21 (as clearly shown in Figure 12).

When the picker is moved upwardly away from the elevator 21 the wires 71 and 72, which are stationary, strike the section of wrapping material 20 carried by the picker 26 and strip the same from the picker. As the section of wrapping material is stripped from the picker a conveyor 113

engages the same and transfers it to the forming box. Before describing the construction and operation of this conveyor mechanism a brief description will be given of the feeler mechanism by means of which the elevator is maintained at a proper position for the picker to contact a section of the wrapping material so long as there is a supply of wrapping material on the elevator.

The automatic operation of the elevator

The feeler mechanism really consists of means for progressively raising the elevator as the supply of wrapping material carried thereon is diminished. This mechanism is dependent for its actuation upon the movement of the picker. When the supply of wrapping material on the elevator has been lowered to a point where the picker will just barely contact the wrapping material the throw of the picker is sufficient to actuate the mechanism for raising the elevator slightly. Sometimes the elevator will be moved at each stroke of the picker, as when there is an adequate supply of wrapping material on the elevator, which is compressed at each stroke of the picker. On the other hand when the supply of wrapping material on the elevator is approaching exhaustion, the elevator may not be moved except once for every several strokes of the picker. The mechanism for raising the elevator is shown best in Figures 2, 10, 12, 16, 17 and 17A.

As shown in Figures 12 and 16, a series of vertically positioned rack teeth 74 are secured to one side of the elevator 21. These teeth mesh with the teeth of a gear wheel 75 carried by shaft 76. Shaft 76 has secured to its outer extremity exteriorly of the casing 10 a hand wheel 76a by means of which the shaft may be rotated manually. There is secured to shaft 76 adjacent the gear wheel 75 a clutch member 77, which cooperates with clutch member 78 to transfer the driving force to shaft 76. Shaft 76 floats within the clutch portion 78 and is not connected thereto. A worm wheel 79 is mounted upon clutch portion 78. It is rotated by a worm gear 80 mounted upon shaft 81.

A ratchet wheel 82 is secured to one extremity of shaft 81. Ratchet wheel 82 is actuated by a pawl 84 carried by a carrier 83 pivotally connected to shaft 81. The carrier 83 is also pivotally connected to one extremity of a pitman 85. The opposite extremity of pitman 85 is secured to the picker pitman 35 as best shown in Figure 10. At the extreme lower stroke of pitman 85 pawl 84 is moved to the right (Fig. 17) into engagement with the next tooth on wheel 82. On the upstroke of pitman 85 pawl 84 causes a partial rotation of wheel 82 and shaft 81. Pawl 84 is held in position by means of a spring 84a secured to carrier 83.

Thus it will be seen that the actuation of shafts 81 and 76 is dependent upon the cam movement utilized for the actuation of the picker 26. In this manner the progressive upward movement of the elevator 21 is controlled by the movement of the picker.

The upward movement of the elevator 21 is dependent upon the extent of the downward stroke of picker 26. This is accomplished through a novel cam arrangement. The cam 36 which actuates picker 26 through the movement of pitman 35 is shown in Figure 17A. The pitman 85 and associated ratchet mechanism are of suitable proportions and so secured to pitman 35 as to cause an index of ratchet wheel 82 only when the roller 86 associated with pitman 35 is at the lowermost portion 87 of the cam surface of cam 36.

Roller 86 can only reach this lowermost portion 87 of cam 36 when spring 33a forces picker 26 to its lowermost position.

When the supply of wrapping material on the elevator 21 is at a height sufficient to prevent spring 33a from forcing picker 26 to its lowermost position then the roller 86 associated with pitman 35 does not engage surface 87 of cam 36 with the result that there is no movement of the elevator 21. On the other hand when the supply of wrapping material on elevator 21 has been reduced to a height whereby spring 33a may force picker 26 to its lowermost position then roller 86 contacts surface 87 of cam 36 and the stroke of pitman 85 is long enough to cause a partial rotation of shaft 81 through the action of pawl 84 upon ratchet wheel 82. This partial rotation of shaft 81 is transferred to gear 75 and thence to elevator 21 through the worm and gear 80 and 79, the clutch 78 and 77 and the shaft 76.

Thus it will be seen that the indexing mechanism by means of which the elevator is progressively raised to position the wrapping material for contact by the picker 26 is actuated only when the picker can no longer contact the wrapping material. So long as the downward movement of the picker is limited by striking the wrapping material 20 on the elevator 21 the indexing mechanism does not operate. In this manner the position of the elevator is made directly responsive to the requirements of the picker.

The driving mechanism of the entire machine is operated by an electrical motor. The electrical current to the motor passes through a switch box 12 secured to the frame 10 (Figure 17). The power mechanism will be described in detail later. At the present time there will be described the mechanism for automatically throwing the switch in switch box 12 whenever the supply of wrapping material on elevator 21 is exhausted and for automatically preventing the operation of the machine while the elevator is in its lowered position as when the supply of wrapping material is being replenished.

The safety switch

Referring particularly to Figure 17 it will be observed that the elevator 21 is provided with a longitudinal groove 88 in one side thereof. This groove terminates at its upper extremity in a cam surface 89 and at its lower extremity in a stop 90. A trip arm 91 is pivotally mounted at 94 on a frame member 21b with the opposite extremities of the frame located in the groove 88. The upper extremity of arm 91 is provided with a cam surface 92 adapted to engage cam surface 89 and its lower extremity is provided with a stop 93 adapted to engage the stop 90.

Bracket 91a is rigidly connected to arm 91 by screws 95. The upper extremity of arm 91 is connected to a toggle mechanism indicated generally at 96 by means of a link 97. The toggle mechanism 96 includes a lever 98 engaging switch lever 99 depending from switch box 12.

When the elevator 21 reaches its upper limit of its travel stop 90 contacts the stop 93 on arm 91 causing the upper extremity of arm 91 to be pivoted slightly about pivot 94 to the left (Figure 17). This slight pivotal movement of arm 91 is transmitted to the switch lever 99 through the link 97, the toggle 96, and the lever 98. In this manner the switch controlling the power drive for the machine is thrown to the off position.

When the elevator 21 is lowered for the purpose of replenishing the supply of wrapping material 78

in the manner which will be described presently the cam surface 89 at the upper extremity of groove 88 contacts cam surface 92 at the upper extremity of arm 91. This arm 91 is again pivoted to the left and throws the switch contained in switch box 12 making the machine inoperative so long as the elevator is in its lowered position.

Means is also provided whereby an operator may throw the switch in switch box 12 by pressing on a foot pedal, not shown. This mechanism consists of a link 100 pivotally connected at its upper extremity to bracket 91a and pivotally connected at its lower extremity to link 101. Link 101 is in turn pivotally connected to a bottom frame portion 102. There is associated with link 101 a foot pedal which can be reached by an operator standing alongside the machine. By pressing on the foot pedal bracket 91a and arm 91 are rotated in a counter clockwise direction about the pivot 94 which actuates the switch in switch box 12 as in the other two cases just described.

The manual operation of the elevator

As previously mentioned shaft 76, which drives the gear wheel 75 engaging the teeth 74 on the side of elevator 21, floats within the clutch portion 78 and has secured thereto exteriorly of the casing 10 a hand wheel 76a. When the clutch consisting of the parts 77 and 78 is disengaged the elevator 21 may be readily raised or lowered by rotating the hand wheel 76a.

The mechanism for thus disengaging the clutch is best shown in Figures 16 and 17. As there shown, a handle 103 projecting exteriorly of the casing 10 is pivotally connected to a lever 104 which is supported by bracket 105 and in turn pivotally connected to a link 106. Link 106 is connected to clutch portion 77 through toggle link mechanism 107-108. The opposite extremity of link 108 is pivotally connected to a bracket 109. When handle 103 is pulled outwardly clutch portion 77 is forced against the compression of spring 110 away from clutch portion 78, thereby disengaging shaft 76 from the operating mechanism of the machine. While the clutch is thus disengaged the elevator may be freely raised and lowered by rotating the hand wheel 76a.

Thus far there has been described the elevator which carries the wrapping material, the picker which removes the wrapping material from the elevator, the adhesive applying mechanism by means of which adhesive is applied to the contact surface of the picker and the mechanism for stripping the wrapping material from the picker. The conveyor mechanism which transfers the section of wrapping material from the stripper to the forming box will now be described.

The conveyor

The conveyor 113 includes a lower support 111 and two fingers 112 (see Figures 12 and 13) mounted thereabove. Conveyor 113 has side portions fitted into longitudinal grooves 114 in tracks 68. The conveyor is reciprocated along the tracks 68 by means of suitable connection with cam 115 (see Figures 2, 8 and 9). Cam 115 is mounted upon a rotatable shaft 115a which is driven from the main drive shaft 39 through suitable drive mechanism.

Cam 115 is operatively associated with the conveyor 113 through means of a pitman 116 pivotally connected to a lever 117. The lower extremity of lever 117 is pivotally connected to a bracket 118 secured to the supporting frame mem-

ber 62. Between the upper extremity of lever 117 and conveyor 113 is positioned a driving link 119 which is pivotally connected to the conveyor 113 at one extremity and pivotally connected to the lever 117 at its other extremity. As cam 115 rotates the conveyor is reciprocated along the tracks 68.

The conveyor and picker operating mechanism are so correlated as to extent and time of movement that the support portion 111 of the conveyor is brought to a position beneath the stripper, and the fingers 112 enter recesses 26a just as the picker 26 begins to move upwardly from the elevator. Consequently, as the section of wrapping material is stripped from the picker it falls upon the support portion 111 of the conveyor; and, as the conveyor continues to move to the right (Figures 12 and 13), the fingers 112 engage the wrapping material as it is released from the picker by the stripper.

After engaging the wrapping material the conveyor moves onwardly to the forming box. There mechanism is provided for removing the section of wrapping material from the conveyor and for properly positioning the wrapping material over the inlet opening of the forming box. This mechanism is shown in Figures 14 and 15 and will now be described.

Wrapping material release and positioning mechanism

At the extreme limit of movement of the conveyor the section of wrapping material 20 carried thereby is positioned over the inlet opening of forming box 17. While in that position a pair of fingers 120 are actuated to engage the longitudinal portion of the wrapping material immediately behind the cross arm portions thereof. Fingers 120 hold the section of wrapping material over the forming box while the conveyor is retracted.

Fingers 120 are slidably connected to stationary supports as indicated at 121. They are pivotally connected to bell cranks 122. The bell cranks are pivotally connected at 123 to support 121. The inner extremities of bell cranks 122 are pivotally connected to links 124. Links 124 are in turn pivotally connected to a vertically reciprocal support 125. The fingers 120 are actuated to engage the section of wrapping material when the support 125 is moved upwardly and to release the wrapping material when the support 125 is moved downwardly.

The mechanism for raising support 125 consists of an arm 126 attached to pin 126a which is pivotally mounted in a bracket 127 secured to cross frame member 67. A cam arm 128 is also rigidly attached to the pin 126a adjacent the bracket 127. At its outer extremity cam arm 128 is provided with a depending bracket 129 having a cam surface at 130. Cam surface 130 is positioned alongside the rack teeth 66 which engage the ratchet wheel associated with the traveling adhesive roller 55. Adjacent the ratchet wheel on roller 55 there is positioned a cam roller 130a adapted to engage cam surface 130.

As the adhesive roller 55 travels to the left (Figure 14) the cam roller 130a contacts cam surface 130 and rotates the arms 128 and 126 associated therewith in a clockwise direction 70 raising the support 125 as indicated by the position of these respective parts in Figure 14. A spring 130b is arranged to hold the arm 128 in its raised position and thereby keep fingers 120 in contact with the wrapping material 20 after 75

the cam roll 130a associated with adhesive roll 55 has passed back (to the right of Fig. 14) over cam surface 130.

Provision is made for applying a positive downward pressure to the upper extremity of support 125 in order to insure satisfactory release of the wrapping material 20 by the fingers 120 at the desired time. The means for exerting this pressure against the upper extremity of support 125 consists of a lateral projecting arm 125a (Figs. 2 and 11) associated with the vertically movable plunger 156 utilized for pressing the block 15 and the wrapping material into the forming box 17. The construction and operation of this plunger will be described presently.

After the section of wrapping material has been removed from the conveyor 113 it is necessary to properly align the same over the inlet opening of the forming box 17. The fingers 120 engage what might be termed the rear end of the section of wrapping material and properly position that end. There is also provided means for aligning what might be termed the forward end of the section of wrapping material. This mechanism consists of a pair of scissorlike fingers 131 (Fig. 15) pivotally mounted at 132. The fingers 131 include integral operating arms 133 which are normally held together by a spring 134. When the arms 133 are together the fingers 131 are in their open position. By spreading the arms 133 the fingers 131 are moved toward each other. Arms 133 are closed by means of a plunger 135 which is carried by block sealing plungers 159, as clearly shown in Figure 11. The construction and operation of this block sealing plunger will be described presently.

By the mechanism just described, the section of wrapping material which is delivered by the conveyor 113 to a position adjacent the forming box 17 is removed from the conveyor and properly aligned over the inlet opening of the forming box. Immediately after this has been done one of the blocks 15 is delivered to a position over the adhesive coated surface of the section of wrapping material, and properly aligned with respect thereto and the inlet opening of the forming box without contacting the wrapping material. The mechanism for delivering the block to a position adjacent the forming box and for aligning the same over the wrapping material and the inlet opening of the box will now be described.

The block transferring and positioning mechanism

The blocks 15 are delivered to the machine in any suitable manner as by a hopper or the like and are received on an endless belt 136 (see Figs. 1, 2 and 11). Belt 136 is mounted upon pulleys 137 and 138 which are in turn mounted upon shafts 139 and 140, respectively (see Fig. 9). Guideways 141 are provided on each side of the upper part of belt 136 for maintaining the blocks in proper position thereon.

Carrier belt 136 delivers blocks 15 to the position shown in Figure 15 where the blocks strike a stop 142. From this point the blocks are transferred one at a time from the carrier belt 136 to a position over the forming box 17 and the wrapping material by a plunger 143 already in position. Plunger 143 is actuated by a cam 144 mounted upon shaft 144a.

The stop 142 (Fig. 15) extends to the edge of the inlet opening of forming box 17. As the block 15 is pushed to the right by plunger 143, it slides

along stop 142 and contacts at its opposite side a resilient guide 145 compressing the guide against the force of spring 146. Guide 145 has an abrupt shoulder at 147. As soon as the back side of the block 15 passes the shoulder 147, guide 145 (due to the action of spring 146) snaps back into the position shown in Figure 15 with the block resting against shoulder 147. A resilient plunger or back stop 148 is positioned to engage the forward face of block 15 before the rear face passes the shoulder 147. Thus, as soon as block 15 does pass the shoulder 147, plunger 148 presses it firmly against the shoulder and against the end of guide stop 142. In this manner the block is properly aligned with the wrapping material and the inlet opening of the forming box 17 while being held in spaced relation to the adhesive coated surface of the wrapping material.

The block and wrapping material at this stage are both in alignment with each other and the inlet opening of the forming box. Before describing the operation by means of which the wrapping material is applied to the block, a brief description will be given of the construction of the forming box itself.

The forming box

The forming box 17 is in reality a box in name only. It is open at its upper surface and there is positioned adjacent each of the four sides of this opening a roller 149 (see Figs. 2, 11 and 14). These rollers are designed to press corresponding portions of the wrapping material against the sides of the block 15. Consequently accurate adjustment of these rollers is required. For that purpose there are provided adjusting screws 150 for each of the four rollers 149. By means of these adjusting screws the rollers 149 may be accurately adjusted to the exact position required to provide the necessary pressure against the side of the block 15.

The box 17 is provided with an outlet opening in a side face adjacent but at right angles to the inlet opening. Rollers are provided at the upper and lower edges of this opening. One of the rollers 149 serves as the upper roller and an additional roller 151 is located adjacent the lower edge of the outlet opening. Adjusting screws 152 similar to the screws 150 are associated with roller 151.

In addition to the inlet and outlet openings for the forming box as just described there are openings in the bottom face of the forming box opposite the inlet opening and in a side face opposite the outlet opening through which plungers project as will be described presently. The outlet opening communicates through a passageway 153 with a discharge tube 154.

The folding and sealing mechanism

The section of wrapping material 20 is folded about and permanently applied to the block 15 by being pressed into and out of the forming box 17 between rollers 149 and 151 by means of a series of reciprocal plungers. First of all a vertical plunger 155 moves into contact with the lower surface of the section of wrapping material 20 while it is in position over the inlet opening of the forming box 17. An upper vertical plunger 156 then moves downwardly and presses the block 15 against the wrapping material 20 as it is held by the plunger 155. Plungers 155 and 156 then both move downwardly. To compensate for any difference in the speed of movement between the two plungers the contact surface 151 of plunger 155 is resiliently mounted upon a spring 75

158. Plunger 156 presses the block and wrapping material between rollers 149 whereby the wrapper is folded along the lines 20e and is pressed against four sides of the block 15 and due to the adhesive coating on the wrapper is permanently sealed thereto.

5 As soon as the block 15 passes between the rollers 149 another plunger 159 presses against one side of the block and forces the block and wrapping material out of the forming box between rollers 149 and 151 thereby pressing the wrapping material against the other two sides of the block. Again, due to the adhesive coating, the wrapping material is permanently sealed to the other two 15 sides of the block as it passes between rollers 149 and 151. Plunger 159 presses the block through outlet tube 153 into discharge tube 154.

10 The manner in which the wrapping material 20 is applied to the block 15 is diagrammatically illustrated in Figures 4 to 7 inclusive. By reference to Figure 4 it will be seen that the block 15 is positioned over the center of the intersecting portions of the wrapping material 20. Initially the block 15 is held in spaced relation to the 15 wrapping material as indicated in Figure 4 by plunger 148 and spring guide 145, previously described, in order to avoid contact with the adhesive contained on the upper surface thereof.

15 As the plunger 156 presses block 15 and wrapping material 20 downwardly between the four rollers 149 the wrapping material assumes the position shown in Figure 5. This downward movement of the block and wrapping material between rollers 149 seals the sections 20a, 20b, 20c and one-half of section 20d of the wrapping material to the four vertical sides of block 15. As soon as the block and wrapping material have passed between the rollers 149 the plunger 159 engages the side of the block to which section 20a of the wrapping material is applied and presses the block and wrapping material out of the forming box between rollers 149 and 151. During this movement the central portion of the wrapping material 20 and the remaining half of section 20d thereof are sealed to the lower and upper sides, respectively, of the block 15. Thus when the block is finally ejected from the forming box by the plunger 159 the wrapping material 20 has been sealed to all six sides of the block. The mechanism for actuating plungers 155, 156 and 159 will now be described.

20 This mechanism is best shown in Figures 2, 8, 9, and 11. The lower extremity of plunger 155 is pivotally connected to one end of a lever 160. The other end of this lever is pivotally connected to a bracket 161 secured to the under side of table 25. A pitman 162 is pivotally connected to lever 160 intermediate its extremities. Pitman 162 is operatively associated with cam 163. Cam 163 is mounted on drive shaft 164. Shaft 164 is rotated from main drive shaft 39 through the drive connection indicated at 165.

25 The plunger 156 is itself in the form of a pitman having its upper extremity associated with cam 166. This cam is mounted on shaft 167 which is driven from auxiliary drive shaft 168 by the drive connection 169. Shaft 168 is rotated by suitable drive connection 170 with shaft 164.

30 The plunger 159 is likewise in the form of a pitman, its outer extremity being operatively associated with cam 171 carried by shaft 168.

35 The movement of cams 163, 166 and 171 are properly timed to provide the desired sequence in the operation of plungers 155, 156 and 159.

After the wrapped block has been ejected from the forming box 17 through the outlet tube 153 into the discharge tube 154, a plunger 172 (see Figs. 14 and 15) pushes the wrapped block along the discharge tube 154 toward the outlet thereof. This plunger is actuated by cam 173 mounted upon drive shaft 144a.

The driving mechanism

40 The driving mechanism illustrated diagrammatically in Figures 8 and 9 will now be described. The source of power for the operation of the machine is an electric motor indicated at 174. Power is delivered from the motor 174 to an auxiliary drive shaft 175 by means of a belt 176. The main drive shaft 39 is driven from auxiliary drive shaft 175 by means of a suitable chain drive 177. The main drive shaft 39 extends completely across the machine as shown in Figure 9 and operates a transversely positioned auxiliary drive shaft 52 through the beveled gears 178.

45 Auxiliary drive shafts 37 and 164 are operated directly from the main drive shaft 39 by the drive connections 38 and 165 respectively. Shaft 115a upon which is mounted cam 115 is driven by shaft 37 through drive connection 179. Auxiliary drive shaft 168 furnishes the motive power for shafts 140 and 167 through the drive connections 180 and 169 respectively. Transverse drive 50 shaft 52 furnishes the driving power for shaft 181 carrying cam 59 through the drive connection 182. Shaft 51 is driven from shaft 181 by the drive connection 183. Shaft 144a is connected to shaft 51 by drive 184.

35

Résumé

55 The machine illustrated and described herein is initially supplied with a quantity of preformed sections of wrapping material 20 and blocks 15 to be wrapped. Wrapping material and blocks are delivered one at a time from opposite ends of the machine to a forming box 17 through which they are forced by plungers 155, 156 and 159 between rollers 149 and 151, whereby the wrapping material is folded about and permanently sealed to the block.

60 The preformed sections of wrapping material are initially placed on an elevator 21. They are removed from the elevator one at a time by a picker 26. Adhesive is transferred to the picker, by means of a roller 55, between each stroke of the picker before it contacts the wrapping material. The picker 26 transfers adhesive to the upper surface of a section of the wrapping material 20 and lifts the same away from the elevator 21. Provision is made for maintaining the elevator 21 at a suitable height for the picker to contact the wrapping material. In order for the picker to contact the wrapping material a portion thereof is projected through stripper wires 71 and 72. As the picker lifts the section of wrapping material away from the elevator the wrapping material is stripped from the picker by the stripper wires 71 and 72.

65 As the section of wrapping material is stripped from the picker 26 by the stripper, conveyor support 111 comes into position beneath the section of wrapping material with the fingers 112 overlying the cross arm portions thereof. The wrapping material is conveyed to a position adjacent the inlet opening of the forming box 17 by the conveyor and is held in this position while the conveyor is retracted by the fingers 120. The fingers 120 in cooperation with fingers 131 auto- 70

65

75

75

75

matically align the section of wrapping material 20 over the inlet opening of forming box 17.

As soon as the section of wrapping material is properly positioned over the inlet opening of forming box 17, a block 15 is transferred from conveyor belt 136 by plunger 143 to a position over the adhesive coated surface of the section of wrapping material. The block is properly aligned with respect to the section of wrapping material and the inlet opening of the forming box 17 by the resilient guide 145 and back stop 148.

As soon as the block 15 and section of wrapping material 20 are in proper alignment with each other and with the inlet opening to forming box 17, plunger 158 is brought into contact with the lower surface of the section of wrapping material. Immediately thereafter the plunger 156 presses block 15 downwardly against contact surface 157 of plunger 158 with the wrapping material between. Plunger 156 presses the block and the wrapping material between rollers 149 whereby the wrapping material is folded about and permanently sealed to the four vertical sides of the block 15.

Plunger 159 then engages a vertical side of block 15 and presses the block and wrapping material out of the forming box between rollers 149 and 151 thereby folding the wrapping material 20 about and sealing the same to the other two sides of block 15.

Plunger 159 presses the wrapped block through outlet tube 153 into discharge tube 154. When the wrapped block enters discharge tube 154 it is forced toward the outlet thereof by plunger 172.

The foregoing description of the operation of the machine embodying the present invention has been necessarily limited to the manner in which the machine operates upon a single section of wrapping material and a single block to be wrapped. However, it should be understood that the complete operation just described is automatically repeated at suitable time intervals to provide for a continuous flow of wrapping material and blocks to the forming box and a continuous discharge of wrapped blocks from the discharge tube.

The invention herein shown and described is exemplified in a machine for permanently applying a wrapper to a wood block. It should of course be understood that the invention is not limited to this particular use but by obvious modifications may be adapted for use in applying various wrappers to various articles which it is desired to wrap. The scope of the invention is indicated in the appended claims.

I claim:

1. An automatic wrapping machine, including in combination, a forming box having inlet and outlet openings, a plurality of rollers arranged adjacent the edges of each of said openings, a conveyor adapted to transfer a section of wrapping material to a position adjacent the inlet opening of the forming box means independent of said conveyor for engaging the edges of the wrapping material to position it in alignment with said inlet opening, means for positioning an article to be wrapped adjacent said section of wrapping material, and means for pressing the article to be wrapped and the section of wrapping material into and out of said forming box between said rollers.

2. An automatic article wrapping machine, including in combination, a forming box having in-

let and outlet openings, a series of rollers positioned adjacent the edges of said openings, means for applying adhesive to a section of wrapping material, a conveyor adapted to transfer the section of wrapping material to a position adjacent the inlet opening of the forming box means independent of said conveyor for engaging the edges of the wrapping material to position it in alignment with said inlet opening, means for positioning an article to be wrapped in spaced relation to the section of wrapping material adjacent said inlet opening, and means for successively pressing said article and said section of wrapping material into and out of said forming box between said series of rollers.

3. An article wrapping machine, including in combination, a forming box having an inlet opening, clamping means arranged at the opposite sides of said inlet opening for engaging a preformed section of wrapping material to align the same with respect to said inlet opening, means for positioning an article to be wrapped in alignment with said inlet opening, a plunger arranged to press said article against said wrapping material and into the forming box through said inlet opening, and means associated with said plunger for causing the clamping means to disengage the section of wrapping material before the plunger presses the article to be wrapped against the wrapping material.

4. An article wrapping machine, including in combination, a forming box having an inlet opening, means for delivering an article to be wrapped to a position adjacent said inlet opening, and means on all sides of said inlet opening for aligning said article with the opening, some of said means being stationary and other of said means being resilient and adapted to press the article against the stationary means.

5. An article wrapping machine, including in combination, a forming box having an inlet opening, a plurality of clamping means arranged about the edges of said opening for engaging a section of wrapping material to align the same with respect to said inlet opening, a plurality of resilient holding means also arranged about said opening adapted to hold an article to be wrapped in alignment with the opening and in spaced relation to the wrapping material, and a plunger arranged to press the wrapping material and the article to be wrapped into the forming box through said opening, the clamping means holding the wrapping material being actuated to disengage the same in response to movement of the plunger.

6. A wrapping machine for applying a wrapper to a square article, including in combination, a forming box having inlet and outlet openings, means for positioning adjacent said inlet opening a section of wrapping material preformed to cover the article to be wrapped without any substantial overlap, means for positioning the article to be wrapped adjacent said section of wrapping material and in alignment with said inlet opening, plunger means for pressing the article to be wrapped and the wrapping material into the forming box through said inlet opening whereby the wrapping material is applied to five sides of the square article, and plunger means for pressing the article and wrapping material out of said forming box through said outlet opening whereby the wrapping material is applied to the sixth side of the article.

7. A wrapping machine for applying a wrapper to a square article, including in combination, a

- forming box having substantially square inlet and outlet openings, rollers arranged alongside all four edges of said inlet opening, rollers arranged alongside two of the edges of said outlet opening, means for positioning adjacent said inlet opening a section of wrapping material preformed to cover the article to be wrapped without any substantial overlap, means for positioning the article to be wrapped adjacent said section of wrapping material and in alignment with said inlet opening, plunger means for pressing the article to be wrapped and the wrapping material into the forming box through said inlet opening whereby the wrapping material is applied to five sides of the square article, and plunger means for pressing the article and wrapping material out of said forming box through said outlet opening whereby the wrapping material is applied to the sixth side of the article.
8. A wrapping machine for applying a wrapper to a square article, including in combination, a forming box having substantially square inlet and outlet openings, rollers arranged along all four edges of said inlet opening, rollers arranged alongside two of the edges of said outlet opening, means for positioning adjacent said inlet opening an adhesive coated section of wrapping material preformed to cover said article without any substantial overlap, means for positioning the article to be wrapped adjacent said section of wrapping material and in alignment with said inlet opening, plunger means for pressing the article to be wrapped and the wrapping material into the forming box through said inlet opening whereby the wrapping material is applied to five sides of the square article, and plunger means for pressing the article and wrapping material out of said forming box through said outlet opening whereby the wrapping material is applied to the sixth side of the article.
9. An article wrapping machine, including in combination, a forming box having an inlet opening, means adjacent said opening for holding a section of wrapping material in position over the opening, stops located at two adjacent sides of the inlet opening, resilient means located at the other two adjacent sides of the inlet opening for holding an article to be wrapped against said stops, and a plunger arranged to press said article and said wrapping material through said inlet opening into said forming box.
10. An article wrapping machine, including in combination, a forming box having an inlet opening, means adjacent said opening for holding a section of wrapping material in position over the opening, stops located at two adjacent sides of the inlet opening, resilient means located at the other two adjacent sides of the inlet opening for holding an article to be wrapped against said stops and in spaced relation to said section of wrapping material, and a plunger arranged to press said article and said wrapping material through said inlet opening into said forming box.
11. An article wrapping machine, including in combination, a forming box having an inlet opening, a reciprocatory conveyor for delivering a preformed section of wrapping material to a position adjacent said inlet openings, and mechanical clamping means adapted to engage the section of wrapping material as it is discharged from the conveyor and to hold the same in aligned position with said inlet opening, at least part of said clamping means being adapted to engage a rearward edge of the wrapping material whereby to prevent return movement of the section of wrapping material with the conveyor when the conveyor moves away from the forming box.
12. An article wrapping machine, including in combination, a forming box having an inlet opening, a reciprocatory conveyor for delivering a preformed section of wrapping material to a position adjacent said opening, and mechanical clamping means adapted to engage the section of wrapping material as it is discharged from the conveyor and to cooperate in aligning the wrapping material with respect to said inlet opening, at least part of said clamping means being adapted to engage the rearward edge of the wrapping material whereby to prevent return movement of the wrapping material with the conveyor when the conveyor moves away from the forming box, and separate clamping means also adapted to engage an edge of the wrapping material remote from said first clamping means for completing the alignment of the wrapping material with respect to said inlet opening.

ALVIN O. SHAFFER.
